HYDROTHERAPY WATER CIRCULATOR

Candido Jacuzzi, Lafayette, and Floyd M. Nash,
Berkeley, Calif.

Application November 15, 1954, Serial No. 33,092

Term of patent 14 years

(Cl. D83—1)

Figure 1 is a view in side elevation of a hydrotherapy water circulator showing our new design.

Figure 2 is a view in front elevation of said apparatus; and

Figure 3 is a top plan view of said apparatus.

We claim:

The ornamental design for a hydrotherapy water circulator, as shown.
